[57] CLAIM

The ornamental design for a bench top liquid test meter, as shown and described.

DESCRIPTION

FIG. 1 is a perspective view of a bench top liquid test meter showing my new design, shown in an exploded condition; FIG. 2 is a front elevational view thereof;

FIG. 3 is a rear elevational view thereof;

FIG. 4 is a top plan view thereof;

FIG. 5 is a bottom plan view thereof;

FIG. 6 is a right hand side elevational view thereof;

FIG. 7 is a left hand side elevational view thereof;

FIG. 8 is a perspective view of a bench top liquid test meter showing a second embodiment of my new design, shown in an exploded condition;

FIG. 9 is a front elevational view thereof;

FIG. 10 is a top plan view thereof;

FIG. 11 is a right hand side elevational view thereof; and, FIG. 12 is a left hand side elevational view thereof.

The rear elevational and bottom plan views of the second embodiment of my design are identical to the same views of the first embodiment, as shown in FIGS. 3 and 5.
